UNITED STATES PATENT OFFICE.

JOHN CHAPMAN, OF SUNDERLAND, ENGLAND.

PLATE FOR SHIP-BUILDING.

SPECIFICATION forming part of Letters Patent No. 737,078, dated August 25, 1903.

Application filed June 6, 1903. Serial No. 160,295. (No model.)

To all whom it may concern:

Be it known that I, JOHN CHAPMAN, a subject of the King of Great Britain and Ireland, residing at and whose post-office address is 45 Offerton street, Millfield, Sunderland, in the county of Durham, England, have invented certain new and useful Improvements in Plates for Ship-Building and other Purposes, (for which I have applied for a patent in Great Britain under No. 14,212, dated June 23, 1902, and in Germany, filed September 2, 1902,) of which the following is a specification.

This invention relates to plates for use in ship-building, bridge-building, the construction of pontoons, gasometers, dock-gates, and other similar purposes; and it is directed to enabling such classes of plating to be effected without the necessity of employing packing at the so-called "landing" and "overlap butt" edges, as is at present required, and, further, to dispense with the operation of "scarfing," whereby time, labor, and expense are reduced and the plating performed in a more expeditious and convenient manner. To attain this end, I "joggle" certain of the plates in a particular manner—that is to say, I form the edges of the plates which are to be overlapped with a "set" at the point where the overlapping takes place sufficient to bring the plates, where hitherto tapered packing was required to effect closure, in the same plane.

As the invention has been primarily devised for ship-building, I will describe the way of carrying it out with respect to such service, reference being had to the accompanying drawings, wherein—

Figure 1 is a front elevation, and Fig. 2 a plan, of four plates riveted together in accordance with my invention. Figs. 3, 4, 5, and 6 are sections on the lines U U, V V, W W, and X X, respectively, in Fig. 1. Fig. 7 is a perspective view of one of the joggled plates alone. Fig. 8 is an elevation showing the mode of joggling where connection is to be made to the stem of the vessel or the like. Figs. 9 and 10 are sections on the lines Y Y and Z Z, respectively, in Fig. 8; and Fig. 11 is a perspective view of one of the joggled plates shown in Fig. 8. Certain parts are

broken away in Figs. 1 and 8 for the sake of clearness.

Referring first to Figs. 1 to 7 of the said drawings, I fashion the overlapping edge, or, as it is sometimes termed, the "overlapped" edge, *a* of each plate *b* of the inner "strake," at the corners *c c* thereof, with a joggle, as shown, so that the corresponding corners *d d* of the overlapping edge, *e* of the adjoining plate are lowered into the same plane therewith, and the landing edges *ff* of the adjoining outer strake-plates *g g* require no packing. Similarly at the point where the overlapping butt edges *h h* of the outer strake-plates meet the landing edge *j* of the inner strake-plate *b* the latter is joggled for a suitable distance to allow of the overlapped plate *g* of the outer strake to be brought into the same plane for the purposes stated. Thus it will be seen the joggling is only required on the plates *b b* of the inner strake, those *g g* of the outer strake being simply overlapped in the usual way. This mode of joggling may be applied to the edges of the plates where connection is to be made to the stem, stern-post, or the like and enables scarfing to be dispensed with, the plates at the same time having the same thickness of material at these points and being consequently in no way weakened. The latter arrangement is illustrated in Figs. 8 to 11, and it will be seen that the inner strake-plate *b* is cut away at the corners to the extent of the breadth or width of the stem *k* or the equivalent part to which it is to be attached and the overlap of the outer strake-plate *g* and that the plate *b* is then joggled in the reverse manner or at right angles to the direction of the joggle formerly described to allow of the plate *g* to be riveted thereto and to the stem without the necessity of scarfing the plate *b* or providing packing.

What I claim as my invention, and desire to secure by Letters Patent, is—

1. In structures where metal plates are joined together a plate overlapped on a plurality of its edges by other plates, said overlapped plate being joggled at a plurality of its corners and at a plurality of its edges so that each overlapping plate is flush with the overlapped plate at points where both the over-

lapped and overlapping plates are overlapped by a third plate.

2. In structures where metal plates are joined together, in combination, a plate jogged at a plurality of its corners, a plate overlapping said plate and flush therewith at the joggled corners, said overlapping plate being joggled at a plurality of its edges, a plate overlapping the two first-named plates and having a corner lying in one of the joggles of the second-named plate and flush therewith at that point.

3. In structures where metal plates are joined together, in combination, a plate jogged at a plurality of its corners, a plate overlapping said plate and flush therewith at the corners, said overlapping plate being joggled on one of its edges, a plate overlapping the

two first-named plates and having a corner lying in the joggles of the second-named plate 20 and flush therewith at that point.

4. In structures where a metal plate is joined to a stem or rib and overlapped by another plate, in combination, a plate having a portion of the metal cut away and joggled at 25 two of its corners, the stem or rib lying flush with the joggled portions of said plate and the plate overlapping said stem or rib and joggled plate and lying flush thereon.

In witness whereof I have hereunto signed 30 my name in the presence of two subscribing witnesses.

JOHN CHAPMAN.
